CONCRETE-TUNNEL FORM.

1,139,335.

Specification of Letters Patent.

Patented May 11, 1915.

Application filed February 29, 1912. Serial No. 680,748.

To all whom it may concern:

Be it known that I, ALFRED A. BREWER, a resident of the city of New York, borough of Manhattan, county and State of New York, have invented certain new and useful Improvements in Concrete-Tunnel Forms, of which the following is a full, clear, and exact description.

My invention relates to collapsible forms for the construction of concrete tunnels, and particularly to those forms which are composed of steel plates with structural iron frames and adapted, when the concrete hardens around them, to be collapsed and moved forward progressively with the formation of the work.

The invention resides in certain special features of construction, which make the forms more easy of construction and more durable and effective in operation, and in various other features of importance, all of which will be fully set forth hereinafter and particularly pointed out in the claims.

For the purpose of a specific description of the preferred form of my invention, which is given as an example only, reference is had to the accompanying drawings, in which—

Figure 1 represents a cross section of a typical concrete tunnel or tube, showing my invention in use therein; Fig. 2 is a fragmentary longitudinal section on the line 2—2 of Fig. 1; and Fig. 3 is a longitudinal section of the tunnel on a reduced scale, showing the manner of using the forms.

The forms are especially adapted for true tunnel work, that is to say, where the concrete tube is cast inside of a completely enclosed tunnel as distinguished from so-called cut and cover work, although, of course, it may be employed in the latter and various other connections without departing from the spirit and scope of the invention.

The form is substantially semi-circular in cross sectional contour, and is so constructed that it may be employed to shape both the invert and the cap or top section of the tube. This allows all of the form sections employed on a job to be of uniform and interchangeable size and construction and greatly decreases the cost of manufacture and increases the facility with which the work may be carried on.

The form itself is composed of a num-

ber of pairs of transversely disposed beams 10, the members of each pair being set parallel web to web and riveted together with the spacer blocks 11 between them. Riveted to each spacer block 11 are pairs of stanchions 12, the members of each pair also formed of channel iron sections, set web to web; and such pairs rising from the beams 10, as shown. At their upper ends, the pairs of stanchions 12 have spacer blocks 14 riveted between their members and these are joined by clamps 15 to ribs 16, which are curved in the arc of the diameter of the tunnel and extend between the stanchions as shown. Steel plates 17 are intended to be placed loosely over the ribs 16, and such plates are stiffened and reinforced by angle irons 18 longitudinally disposed between the beams or ribs 16. The purpose of the loose plates 17 will be fully set forth hereinafter.

The several spacer blocks 14 at each side of the form carry pintle rods 19, on which the hinge butts 20 are mounted. These hinge butts 20 are joined to arc-shaped ribs 21, which extend from the rods 19 downward to the beams 10 along the contour of the tunnel and have steel plates 22 affixed thereto. These plates 22 are reinforced by angle iron ribs 23 and serve with the ribs 21 to form rigid wings at each side of the mold, which wings, however, may swing in and out around the pintle rods 19. When the parts are extended into operative position, as shown in Fig. 1, the plates 17 and 22 lie in a true semi-circle to give the tunnel its true circular form, but when the concrete has hardened around the mold or form, the wings at each side may be drawn in and the form dropped, disengaging it from the concrete and allowing the form to be advanced, as will hereinafter fully appear. The ribs 21 have their lower ends loosely received between the ends of the members of the pairs of beams 10 and are guided thereby in their inward and outward movement. Said lower ends of the ribs 21 have lugs 24 thereon located respectively above and below the beams 10; and these lugs are adapted to have turnbuckles 25 engage therewith. The turnbuckles extend inward and are adapted to be connected with lugs 11^a on the spacer blocks 11. These lugs 11^a are also located above and below the beams 10. By means of these

turnbuckles, the wings at the side of the form may be moved in or out as described. The lugs 24 and 11^a are located above and below the beams 10, so as to permit a reversal of the position of the turnbuckles when the form is reversed. Thus, as shown in Fig. 1, in the construction of the cap of the tunnel, the turnbuckles are most conveniently located below the beams 10, but if the form is reversed to form the invert or bottom section of the tunnel, it will be most convenient to change the position of the turnbuckle, so that they will lie on the opposite side of the beams 10. This opposite side will then be the under side or, in other words, the side which is uppermost when the form is in the position shown in Fig. 1. In both situations, however, the turnbuckles perform the function above referred to.

The form is adapted to be supported in operative position and transported along the tunnel as the work progresses, by means of a carriage or truck 26, having wheels 27 adapted to run on the invert and arranged to be chocked or wedged against rocking or lateral motion by tapering blocks 27^a or the like driven in between the corners of the truck and the inner surface of the invert of the tunnel. Said carriage mounts a number of jacks 28 and these in turn support longitudinally extending beams 29 into which beams the beams 10 are jogged or sunk, as shown best in Fig. 2, so that in this manner the form is mounted on the truck and is prevented from shifting longitudinally. It may also be raised and lowered by the jack and the whole apparatus moved along the length of the tunnel when it is desired to start a new section of the work.

In the use of the invention, a key or narrow invert section *a* is laid along the longitudinal center of the tunnel at the bottom thereof. This is laid in concrete by any suitable mold or in any other manner and one of the forms is inverted and set on this key. The form is properly wedged to prevent lateral displacement and the concrete is filled in at the sides of the form, meeting the key *a* and extending up to the spring line of the tunnel, that is to say, to the widest horizontal diameter thereof. The form is allowed to set in this position until the concrete is set and the invert is then formed. The bottom or inverted form is then moved forward a section equal to the length of the form, and the operation is repeated. Meanwhile, the truck 26 is wheeled forward into the invert section first formed and a second form in the adjustment shown in Fig. 1 is set up with its side edges meeting the invert which has first been formed, and the cap or top section of the tunnel is molded around the second-named form. The two forms then assume the relative position shown in Fig.

3, which is to say, the bottom form produces the invert and is always at work one section ahead of the cap or top form. The bottom form precedes the cap form for the purpose of producing the invert, and the cap form follows it up by molding the cap to complete the tunnel immediately back of the inverted form. The work in this manner progresses step by step, as Fig. 3 illustrates. The loose plates 17 on the form allow the concrete to be introduced between the walls of the tunnel and the face of the form by bringing the concrete up through the tunnel in a suitable buggy 30 running on rails 31, which are mounted on a stage 80 or the like erected for that purpose in the tunnel independently of the form. As the concrete is charged in around the cap form and rises toward the crown of the arch the plates 17 are one by one replaced to support the concrete as it rises, and finally the last plate is put in position and the remainder of the concrete at the crown of the arch is introduced longitudinally of the tunnel from the front end of the form along the top of the same. When the form is reversed to construct the invert of the tunnel, the plates 17 are, of course, temporarily secured to the ribs 16, and the concrete is charged in past the upper side edges of the 95 reversed or inverted form.

It will be observed that in this manner with the use of two of the forms, the formation of the concrete tube may be properly carried on, the operation proceeding in definite advances and by calculating the length of the forms and the capacity of the plant, it may be arranged so that a day's work will be consumed in forming one cap and the invert section preceding it. This allows 100 the forms to be left *in situ* over night, while the concrete hardens and the next day's work will consist in a second cap and a second preceding invert.

The form may be of uniform construction and their parts, therefore, readily interchanged for adjustment or repair. This not only makes the operation easy, but greatly reduces the expense of operation and maintenance.

Having thus described my invention, what I claim as new and desire to secure by Letters Patent is:

1. A form for constructing concrete tubes, comprising diametric frame beams, additional frame beams extending transversely from one side thereof and a rigid attached frame section between the outer ends of said additional frame beams, hinged wings at the sides of the form extending between said rigid frame section and the ends of the diametric beams and means for moving the said wings in and out.

2. A form for constructing concrete tubes, comprising diametric frame beams, addi-

tional frame beams extending transversely from one side thereof and a rigid arched frame section between the outer ends of said additional frame beams, hinged wings at 5 the sides of the form extending between said rigid frame section and the ends of the diametric beams and means for moving the said wings in and out, the hinges of the wings being located at the ends of the arched 10 frame section.

3. A form for constructing concrete tubes, comprising diametric frame beams, additional frame beams extending transversely from one side thereof and a rigid arched frame section between the outer ends of said additional frame beams, hinged wings at 15 the sides of the form extending between said rigid frame section and the ends of the diametric beams and means for moving the said wings in and out, the hinges of the wings being located at the ends of the arched frame section and said means for moving the wings being located adjacent to the diametric beams.

25 4. A form for constructing concrete tubes, comprising diametric frame beams, additional frame beams extending transversely from one side thereof and a rigid arched frame section between the outer ends of said additional frame beams, hinged wings at the 30 sides of the form extending between said rigid frame section and the ends of the diametric beams and means for moving the said wings in and out, comprising turnbuckles 35 mounted on the diametric beams and extending parallel thereto into connection with the wings.

5. A form for constructing concrete tubes, comprising diametric frame beams, additional frame beams extending transversely from one side thereof and a rigid arched frame section between the outer ends of said additional frame beams, hinged wings at 40 the sides of the form extending between said rigid frame section and the ends of the diametric beams and means for moving the said wings in and out, said means for moving the wings being located alongside of the diametric beams and the form being provided 45 with devices whereby the means for moving the wings may be reversed from one side to the other of the diametric beams, for the purpose specified.

6. A form for concrete work comprising 50 pairs of frame beams, the members of which are spaced from each other, a wing forming section hinged to a frame beam and adapted to move in and out and having a part sliding between the spaced members of said pairs of 55 frame beams and means for so moving the wing form section.

7. A form for concrete work comprising

pairs of frame beams, the members of which are spaced from each other, a wing forming section hinged to a frame beam and adapted 65 to move in and out and having a part sliding between the spaced members of said pairs of frame beams and means for so moving the wing form section, such means located alongside the frame beams and a form provided 70 with devices whereby said means for moving the wing form section may be reversed from one side of the beams to the other, for the purpose specified.

8. A form for concrete work comprising 75 pairs of frame beams, the members of which are spaced from each other, a wing forming section hinged to a frame beam and adapted to move in and out and having a part sliding between the spaced members of said pairs of 80 frame beams and means for so moving the wing form section, comprising a turnbuckle, one end of which is articulated to the frame and the other to the said wing.

9. A form for making concrete tubes, 85 comprising diametric frame beams, each composed of two members spaced from each other, spacer blocks fastened between said members of said beams, additional beams fastened to said spacer blocks, projecting 90 laterally from one side of the diametric beams, an arched crown section with its frame member rigidly joined to the outer end of said additional frame beams and extending between the same, pintle rods at the 95 outer ends of said frame beams, wing sections hinged to said pintle rods to swing in and out and means for moving the wing section.

10. A form for making concrete tubes, 100 comprising diametric frame beams, each composed of two members spaced from each other, spacer blocks fastened between said members of said beams, additional beams fastened to said spacer blocks, projecting 105 laterally from one side of the diametric beams, an arched crown section with its frame member rigidly joined to the outer end of said additional frame beams and extending between the same, pintle rods at the 110 outer ends of said frame beams, wing sections hinged to said pintle rods to swing in and out and means for moving the wing section, the wing sections having parts sliding between and guided by the said spaced members of the frame beams. 115

In testimony whereof I have signed my name to this specification in the presence of two subscribing witnesses.
